(74) *Attorney, Agent, or Firm* — Sheridan Ross P.C.

(57) **CLAIM**

The ornamental design for a mounting plate for a patient support cart, as shown and described.

DESCRIPTION

FIG. 1 is a front perspective view of a mounting plate for a patient support cart showing my new design;

FIG. 2 is a front elevation view of thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a front perspective view thereof, attached to a patient support cart, and showing attached blood pumps and an oxygenator as environment.

The dashed lines shown in the figures represent environment and form no part of the claimed design.

1 Claim, 5 Drawing Sheets
